US00D815931S

(12) **United States Design Patent** (10) Patent No.: **US D815,931 S**
(45) Date of Patent: **** Apr. 24, 2018**

- (54) **REAR WINDOW SETTING BLOCK**
(71) Applicant: **Dell Skluzak**, Lakewood, CO (US)
(72) Inventor: **Dell Skluzak**, Lakewood, CO (US)
(**) Term: **15 Years**
(21) Appl. No.: **29/577,708**
(22) Filed: **Sep. 15, 2016**
(51) LOC (11) Cl. **08-05**
(52) U.S. Cl. **USPC D8/14**
